TIRE

Leonard C. Youngblood, Grosse Pointe Park, Mich., assignor to United States Rubber Company, New York, N.Y., a corporation of New Jersey

Filed July 12, 1965, Ser. No. 86,120

Term of patent 14 years

(Cl. D90—20)

Fig. 1

*Fig. 2**Fig. 3*FIG. 1 is a perspective view of a tire embodying my new design, it being understood that the full line portion is repeated throughout the circumference of the tire, shown by means of broken lines;

FIG. 2 is an enlarged fragmentary plan view of the full line portion shown in FIG. 1; and

FIG. 3 is a sectional view taken substantially on the plane indicated by line III—III of FIG. 2, but on a reduced scale.

The dominant features of my design reside in those portions shown in full lines in the drawings.

I claim:

The ornamental design for a tire, substantially as shown and described.
